UNITED STATES PATENT OFFICE.

RAFAEL GUASTAVINO, OF NEW YORK, N. Y., ASSIGNOR TO FRANCESCA RAMIREZ GUASTAVINO AND BERNARD S. LEVY, BOTH OF SAME PLACE.

FIRE-PROOF BUILDING.

SPECIFICATION forming part of Letters Patent No. 336,047, dated February 9, 1886.

Application filed July 18, 1885. Serial No. 171,971. (No model.)

To all whom it may concern:

Be it known that I, RAFAEL GUASTAVINO, a citizen of the United States, and a resident of New York, in the county of New York and State of New York, have invented certain new and useful Improvements in Fire-Proof Buildings, of which the following is a specification.

My present invention relates to the construction of fire-proof buildings, and it has to special reference to the stairs of such buildings.

My invention is applicable to buildings of all descriptions—such as private dwellings, factories, theaters, school-houses, warehouses, &c. The object of the invention is to devise a more economical plan of constructing the stairways of fire-proof buildings, and also to insure the production of thoroughly substantial structures, which shall combine economy, solidity, and incombustibility. Stairways erected according to my invention are also comparatively light in weight. The vaults upon which the stairs are built are also free from the usual cavities and joints, and when completed have the appearance of solid stones without solution of continuity.

The features of novelty for which I desire protection are pointed out in the claims at the end of this description.

Referring to the accompanying drawings, which form part of this description, and in which like letters indicate like features, Figure 1 shows a vertical section of a stairway embodying my invention, taken through the line A B, Fig. 3. Fig. 2 is a front elevation. Fig. 3 is a plan view. Fig. 4 is a face view of one of the vaults, showing tiles of two layers arranged so as to break joints, and Fig. 5 is a cross-section of the stairway, taken through the line C D, Fig. 1.

Ordinary brick are not well adapted for use in the erection of stairways according to my invention. I by preference use brick tile of about three-fourths of an inch thick, about four to six inches wide, and from eight to twelve inches long.

The vaults supporting the stairs are composed of two or more layers of tiles set in cement or plaster-of-paris, and when such layers are united together in such manner as to break joints a structure is produced having

a surface without solution of continuity, and resembling a large stone of several inches in thickness.

The stairways may be constructed in a series of flights, supported one above another, with landings on the floor of each story, or intermediate between the floors, or both, if found desirable; or they may be in one continuous winding flight extending from bottom to top of the building.

The stairway shown in Fig. 1 of the drawings may be of any practicable number of feet in length. The foundation of this stairway (shown at E) is constructed of tiles and cement of sufficient thickness to afford a secure bearing. The foot of the vault F rests in a depression in the foundation E, as shown, in which depression is the angle-iron b, which is of the same length as the width of the foot of the vault F.

The vault F is, as stated, composed of two or more layers of tile, as shown, which are united together by plaster-of-paris or cement, and in such manner as to break joints, as clearly shown in Fig. 4. The structure when completed in this manner is of great strength, and while considerably lighter than a stone or granite vault is equally as durable and much more economical.

Fig. 5 shows the form of the vault in cross-section, indicating particularly the curve of the vault from side to side and the angle-iron a, which is secured on the exposed edge of the vault for the purpose of protecting it. The platform or landing G is preferably of slate, and is supported upon a foundation, h, of tile set in cement, which rests upon the vault F. The steps H and risers J, which are also preferably of slate, are likewise supported on foundations, h, of tile set in cement erected upon the vault F, as shown. The tile composing the foundations h may be of two or more layers set in cement or plaster-of-paris, and which may be arranged so as to break joints. When thus constructed, such foundations are essentially the same as solid stones and quite as durable.

Having thus described my invention, what I claim as new, and desire to secure by Letters Patent, is—

1. A vault for stairways, composed of two

or more layers of brick tile united together by cement or plaster-of-paris, substantially as set forth.

2. A vault for stairways, composed of two or more layers of brick tile united together so as to break joints by cement or plaster-of-paris, substantially as set forth.

3. A staircase having a supporting-vault composed of two or more layers of brick tile, and step-supports, also composed of two or more layers of brick tile, the tile in both cases being united together by cement or plaster-of-paris, substantially as set forth.

4. A staircase consisting of a vault composed of two or more layers of brick tile, step supports, also of two or more layers of brick tile, the tile in both cases being united together by cement or plaster-of-paris, and arranged so as to break joints, substantially as set forth.

5. A vault for stairways, composed of two or more layers of brick tile united together by cement or plaster-of-paris, in combination with the angle-iron *a*, substantially as set forth.

6. A vault for stairways, composed of two or more layers of brick tile united together by cement or plaster-of-paris, in combination with a foundation, *E*, also composed of brick tile united together by cement or plaster-of-paris, substantially as set forth.

7. A vault for stairways, composed of two or more layers of brick tile united together by cement or plaster-of-paris, in combination with a foundation of brick tile, likewise united together by cement or plaster-of-paris, and an angle-iron, *a*, substantially as set forth.

8. A vault for stairways, composed of two or more layers of brick tile united together by cement or plaster-of-paris, in combination with the angle-iron *b*, substantially as set forth.

Signed at New York, in the county of New York and State of New York, this 7th day of July, A. D. 1885.

RAFAEL GUASTAVINO.
